UNITED STATES PATENT OFFICE.

ROBERT W. KALTENBACH AND JUSTIN GRIESS, JR., OF CLEVELAND, OHIO.

EXCAVATING, HOISTING, AND CONVEYING BUCKET.

No. 804,235.

Specification of Letters Patent.

Patented Nov. 14, 1905.

Application filed July 8, 1904. Serial No. 215,748.

To all whom it may concern:

Be it known that we, ROBERT W. KALTENBACH and JUSTIN GRIESS, Jr., citizens of the United States of America, residing at Cleveland, in the county of Cuyahoga and State of Ohio, have invented certain new and useful Improvements in Excavating, Hoisting, and Conveying Buckets; and we do hereby declare the following to be a full, clear, and exact description of the invention, such as will enable others skilled in the art to which it pertains to make and use the same.

This invention relates to improvements in excavating, hoisting, and conveying buckets, and pertains more especially to a clam-shell bucket comprising two oppositely-arranged scoops or trays having cutting edges at the bottom and forward ends and pivotally supported, as required, to render them capable of being swung from and toward each other to open and close the bucket, respectively.

One object of this invention is to so relatively arrange the parts of the tray-actuating mechanism of the bucket as will bring the center of gravity of the bucket low down and prevent tipping of the bucket when the bucket is landed on an uneven pile of material.

Another object is to pivotally attach the bars or links which are pivotally connected to the rear portions of the trays to a bail with which the bucket is centrally provided, with the pivotal connections between the said bars or links and the said bail arranged below the axes of the levers, so as to most advantageously place the trays of the bucket when open relative to the pile or bed of material to be excavated or operated upon.

Another object is to use the bail of the bucket as a means for holding the bucket and in guiding all of the cables of the bucket.

Another object is to attach the cables which are employed in holding the bucket at the desired elevation preparatory to permitting the trays of the bucket to separate by gravity, and thereby open the bucket to clevises directly pivoted to rear portions of the trays with the relative arrangement of the parts such that any strains upon the trays and connected mechanism are equally distributed and that multiplication of power in opening the bucket is not necessary.

With these objects in view and to the end of realizing other advantages hereinafter appearing this invention consists in certain features of construction and combinations of

parts hereinafter described, and pointed out in the claims.

In the accompanying drawings, Figure 1 is a side elevation of a clam-shell bucket and connected bucket-operating mechanism embodying our invention, and in this figure the bucket is shown closed. Fig. 2 is a right-hand side elevation relative to Fig. 1. Fig. 3 is a side elevation of the bucket and connected mechanism with the bucket open. Fig. 4 is a top plan relative to Fig. 3.

Referring to the drawings, A and A' indicate two oppositely-arranged scoops or trays, which form the body portion of our improved clam-shell bucket. The trays A and A' swing rearwardly from or forwardly toward each other, according as the bucket is opened or closed. The bucket illustrated is shown closed in Figs. 1 and 2 and open in Figs. 3 and 4. Each tray is provided at its rear end and near the top thereof with an axle α , which is arranged horizontally and transversely of the said tray. The axles α of the two trays are parallel and arranged in the same plane horizontally. The trays A and A' in opening and closing swing in a vertical plane upon the axles α .

Each axle α has bearing in the rear ends of two parallel bars B, which are arranged at opposite sides, respectively, of the tray 85 journalled on the said axle, and in the closed position of the bucket, as shown in Figs. 1 and 2, extend upwardly as well as forwardly relative to the said tray. It will be observed, therefore, that the trays A and A' have bearing on the axles α and that the latter have bearing in the rear ends of the bars B. The bars B are pivoted at their forward ends, as at b , horizontally and parallel with the axles α to the lower ends of the end members 12 95 and 13 of a bail whose upper and central portion comprises two horizontal axles 14 and 15, which are arranged in the same plane horizontally and parallel with each other and with the axles α . The axles 14 and 15 have bearing in the upper ends of both end members 12 and 13 of the said bail.

Two levers C and C' are operatively attached to the tray A. Two levers D and D' are operatively attached to the tray A'. The levers C 105 C and D D' are fulcrumed horizontally and parallel with the axes of the trays to the bail members 12 and 13. The levers C C' and D D' have their fulcrums coincident and formed by horizontally-arranged axles 16 and 17, 110

which extend through the bail members 12 and 13, respectively, a suitable distance above the lower extremities of the said bail members, but preferably a greater distance below 5 the upper extremities of the said bail members. The axles 16 and 17 are parallel with the axes of the trays and arranged in line endwise. The bail members 12 and 13 are preferably tied together and braced apart be- 10 tween their upper ends and the fulcrums of the levers C and D (see Figs. 2 and 4) by a frame or web 8, formed in any approved manner and rigid with the said bail members. The levers C C and D D extend forwardly 15 and upwardly from the connected tray, and the levers C C cross the levers D D at the fulcrums of the levers and above the connection of the said levers with the trays. The levers C C are shown pivoted at their lower 20 ends, as at 18, to opposite sides, respectively, of the tray A, horizontally and parallel with the axis of the said tray, at the upper portion of the forward end of the tray. The levers D D are pivoted at their lower end, as at 20, to op- 25 posite sides, respectively, of the tray A', horizontally and parallel with the axis of the said tray, at the upper portion of the forward end of the tray. It will be observed, therefore, that the levers C and D at one side of the 30 bucket are fulcrumed to the bail member 13 by means of the axle 16, that the levers C and D at the opposite side of the bucket are fulcrumed to the bail member 12 by means of the axle 17, that the said axles or fulcrums 35 16 and 17 are located above a point centrally between the ends of the levers, that the pivotal connections between the bars B and the bail members 13 and 14 are arranged below the fulcrums of the levers C and D, and that 40 the axes of the pivotal connections between the said bars and the said bail members are all preferably arranged coincidently and vertically below the fulcrums of the aforesaid levers, as shown.

45 The levers C and C are connected together and braced apart at and above their axes (see Figs. 2 and 4) by a frame c, which is journaled upon the axles 16 and 17 and connected at the top to the said levers, preferably by 50 axles 22, which are horizontally arranged parallel with the axes of the said levers and in line endwise and attached to and borne by the said frame and the said levers. The levers D and D are connected together and braced 55 apart at and above their axes (see Figs. 2 and 4) by a frame d, which is journaled upon the axles 16 and 17 and connected at the top to the said levers, preferably by axles 24, which are horizontally arranged parallel with the 60 axes of the said levers and in line endwise and attached to and borne by the said frame and the said levers. Upon each axle 22 is loosely mounted a guide-sheave 23, and upon each axle 24 is loosely mounted a guide-sheave 65 25

Two bucket-closing cables G and G are suitably attached at one end to the axle 14, thence lead downwardly to and around the sheaves 25, connected with the upper ends of the levers D, thence lead in under the sheaves 23, 70 connected with the upper ends of the levers C, thence lead into engagement with guide-sheaves 26, which are loosely mounted on the axle 15, and thence lead to winding drums or means (not shown) employed in operating 75 the said cables. The levers C are provided at their upper ends with guards 27, arranged to prevent displacement of the cables G from the sheaves 23. The levers D are provided at their upper ends with guards 28, arranged 80 to prevent displacement of the cables G from the sheaves 25.

The upper portions of the levers D are provided with laterally-projecting stop-forming lugs 30, which are engaged by the levers C 85 in the full-open position of the bucket and limit the movement of the levers as required in operating the levers to separate the trays A and A' in opening the bucket.

Upon each axle a, between the bars B, connected with the said axle, is journaled a clevis L. Two bucket-holding cables R and R are operatively attached in any approved manner to the clevis of the different axles a and a, respectively, and lead from the connected clevis 90 upwardly to and in under guide-sheaves 34 and 35, respectively, which are loosely mounted on the axles 14 and 15, respectively. (See Figs. 2 and 4.) The axles 14 and 15 are provided with a guard 32, arranged to prevent 95 displacement of the cables R from the sheaves 34 and 35, which guard extends over the said sheaves and is provided with holes 33, arranged to accommodate the extension of the said cables through the guard upwardly from the sheaves. The cables R are operated in any approved manner. Cable-operating devices are too well known in the art to require illustration and description in this application.

It will be observed that the bucket hereinbefore described is simple and durable in construction and reliable in its operation; that the bucket-trays A and A' are when the bucket is laden and closed and suspended over a pile or bed of material opened by the gravity of the bucket and contents upon holding the cables R and releasing the bucket-closing cables G; that the bucket when open is closed by actuating the levers C and D upon winding up or pulling on the cables G; that the bars B are attached to the end members of the bail below the fulcrums or axes of the levers C C and D D, so as to accommodate the actuation of the trays in closing or operating the bucket 10 independently of each other and to enable the trays upon opening the bucket to assume a position vertically on end or with the rear ends nearer to each other than their forward ends; that the arrangement of the parts gen- 11

erally is such that the tray-actuating mechanism and the center of gravity of the bucket are exceptionally low down relative to the cutting edges of the trays when the bucket is open, so that the liability of the bucket to tip when the said bucket is landed upon an uneven pile or bed of material is reduced to a minimum; that all of the sheaves employed in guiding the bucket-holding cables R upwardly from the bucket above the bucket-closing levers are borne by the upper portion (axles 14 and 15) of the bail of the bucket, and that the cables R, are attached, by means of clevises, to the axles a independently of the attachment to the said axles of the bars B and between the said bars, so that the connection of the cables R with the trays is most direct, that the opening of the bucket is readily effectible without any multiplication of power, and any strains upon the trays and connected mechanism are equally distributed.

What we claim is—

1. In a bucket whose body portion is composed of suitably-supported trays arranged to swing outwardly and upwardly or inwardly and downwardly according as the bucket is opened or closed, the combination of the said trays; a bail arranged centrally and transversely of the bucket; bucket-closing levers operatively attached to the trays and fulcrumed to the bail with the axes of the levers coincident and parallel with the axes of the trays; bars pivotally connected, at one end, to the trays at the rear ends of the trays and pivotally supported, at the other end, below the fulcrums of the levers, and means for operating the levers.

2. In a bucket whose body portion is composed of suitably-supported trays arranged to swing outwardly and upwardly or inwardly and downwardly according as the bucket is opened or closed, the combination of the said trays; a bail arranged centrally of the bucket; levers operatively attached to the trays and suitably fulcrumed to the lower portion of the bail; bars pivotally connected, at one end, to the rear portions of the trays and pivotally supported, at the other end, below the fulcrums of the levers, and means for operating the levers.

3. In a bucket whose body portion is composed of suitably-supported trays arranged to swing outwardly and upwardly or inwardly and downwardly according as the bucket is opened or closed, the combination of the said trays; a bail arranged centrally of the trays; bucket-closing levers operatively attached to the forward portions of the trays and suitably fulcrumed to the bail; bars pivotally connected, at one end, to the rear portions of the trays, and pivoted, at the other end, to the bail below the fulcrums of the levers, and means for operating the levers.

4. In a bucket whose body portion is composed of suitably-supported trays arranged to

swing outwardly and upwardly or inwardly and downwardly according as the bucket is opened or closed, the combination of the said trays; a bail arranged centrally and transversely of the bucket; levers operatively attached to the forward portions of the trays and suitably fulcrumed to the bail; bars pivotally connected at one end, to the rear portions of the trays, and pivoted, at the other end, to the bail below the fulcrums of the levers, and means for operating the levers.

5. In a bucket whose body portion is composed of suitably-supported trays arranged to swing outwardly and upwardly or inwardly and downwardly according as the bucket is opened or closed, the combination of the said trays; a bail arranged centrally and transversely of the bucket; levers operatively attached to the trays at the forward ends of the trays and fulcrumed to the bail, with the axes of the levers coincident and parallel with the axes of the bucket-sections; bars pivotally connected, at one end, to the rear portions of the trays, and pivoted, at the other end, to the end members of the bail below the fulcrums of the levers, with the axes of the pivotal connections between the said bars and the bail coincident, and means for operating the levers.

6. In a clam-shell bucket having two oppositely-arranged suitably-supported trays arranged to swing from or toward each other according as the bucket is opened or closed, the combination of the said trays; an upright bail arranged centrally and transversely of the bucket and having end members arranged a suitable distance apart laterally; levers operatively attached to the trays and fulcrumed to the end members of the bail with the axes of the levers coincident and parallel with the axes of the trays; bars pivotally connected, at one end, to the trays rearwardly of the levers and pivotally supported, at the other end, below the fulcrums of the levers, and means for operating the levers.

7. In a clam-shell bucket having two oppositely-arranged suitably-supported trays arranged to swing from or toward each other according as the bucket is opened or closed, the combination of the said trays; an upright bail arranged centrally and transversely of the bucket and having end members arranged a suitable distance apart laterally; levers operatively attached to the trays at the forward ends of the trays and suitably fulcrumed to the end members of the bail between the central portions and lower extremities of the said bail members; bars pivotally connected, at one end, to the rear portions of the trays and pivotally supported, at the other end, below the fulcrums of the levers, and means for operating the levers.

8. In a clam-shell bucket having two oppositely-arranged suitably-supported trays arranged to swing from or toward each other according as the bucket is opened or closed,

the combination of the said trays; a bail arranged centrally and transversely of the bucket and having end members arranged a suitable distance apart laterally; levers operatively attached to the trays at the forward ends of the trays and suitably fulcrumed to the end members of the bail; bars pivotally connected, at one end, to the trays rearwardly of the levers, and pivoted, at the other end, to the end members of the bail below the fulcrums of the levers, and means for operating the levers.

9. In a clam-shell bucket having two oppositely-arranged trays arranged to swing from or toward each other according as the bucket is opened or closed, the combination of the said trays; a bail arranged centrally and transversely of the bucket and having end members arranged a suitable distance apart laterally; levers operatively attached to the trays at the forward ends of the trays and suitably fulcrumed to the end members of the bail; bars pivotally connected, at one end, to the rear portions of the trays, and pivoted, at the other end, to the end members of the bail vertically below the fulcrums of the levers; means for operating the levers, and cables connected to the rear portions of the trays.

10. In a clam-shell bucket having two oppositely-arranged trays arranged to swing from or toward each other according as the bucket is opened or closed, the combination, of the said trays; a bail arranged centrally between and transversely of the bucket and having end members arranged a suitable distance apart laterally; levers operatively attached to the forward portions of the trays and fulcrumed to the end members respectively of the bail, with the axes of the levers parallel with the axes of the trays and coincident; bars pivotally connected, at one end, to the rear portions of the trays, and pivoted, at the other end, to the end members of the bail below the fulcrums of the levers, with the axes of the pivotal connections between the said bars and the said bail members coincident; means for operating the levers, and cables connected to the rear portions of the trays.

11. In a clam-shell bucket having two oppositely-arranged suitably-supported trays arranged to swing from or toward each other according as the bucket is opened or closed, the combination of the said trays; a bail arranged centrally and transversely of the bucket and having end members arranged a suitable distance apart laterally; two levers operatively attached to opposite sides respectively of the forward portion of one of the trays and suitably fulcrumed to the bail; two levers operatively attached to opposite sides respectively of the forward portion of the other of the said trays and suitably fulcrumed to the different end members respectively of the bail and crossing the first-mentioned levers; bars pivotally connected, at one end, to the rear

portions of the trays, and pivotally supported, at the other end, below the fulcrums of the levers, and cables operatively connected with the levers.

12. In a clam-shell bucket having two oppositely-arranged suitably-supported trays arranged to swing from or toward each other according as the bucket is opened or closed, the combination of the said trays; a bail arranged centrally and transversely of the bucket and having end members arranged a suitable distance apart laterally; two levers attached to opposite sides respectively of the forward portion of one of the trays and fulcrumed to the different end members respectively of the bail; means tying together and bracing apart the said levers; two levers operatively attached to opposite sides respectively of the forward portion of the other of the trays and fulcrumed to the different end members respectively of the bail and crossing the first-mentioned levers, with the axes of all of the said levers parallel with the axes of the trays and coincident; means tying together and bracing apart the second-mentioned levers; bars pivotally connected, at one end, to the rear portions of the trays, and pivoted, at the other end, to the end members of the bail below the fulcrums of the levers, and cables operatively connected with the levers.

13. In a clam-shell bucket having two oppositely-arranged suitably-supported trays arranged to swing from or toward each other according as the bucket is opened or closed, the combination of the said trays; a bail arranged centrally between and transversely of the bucket and having end members arranged a suitable distance apart laterally and a frame or web between and connecting the said bail members together; levers operatively attached to the forward portions of the trays and suitably fulcrumed to the end members of the bail; bars pivotally connected at one end, to the rear portions of the trays, and pivoted, at the other end, to the end members of the bail below the fulcrums of the levers, and means for operating the levers.

14. In a clam-shell bucket having two oppositely-arranged trays arranged to swing from or toward each other according as the bucket is opened or closed, the combination of the said trays; a bail arranged centrally and transversely of the bucket; levers operatively attached to the sides of the forward portion of one of the trays and suitably fulcrumed to the bail; levers operatively attached to the sides of the forward portions of the other of the said trays, and suitably fulcrumed to the bail and crossing the first-mentioned levers; bars pivotally connected, at one end, to the rear portions of the trays, and pivotally supported, at the other end, below the fulcrums of the levers; cables operatively connected with the levers, and other cables connected to the rear portions of the trays.

15. In a clam-shell bucket having two oppositely-arranged suitably-supported trays arranged to swing from or toward each other according as the bucket is opened or closed, 5 the combination of the said trays; a bail arranged centrally and transversely of the bucket; two horizontally-arranged axles borne by the bail a suitable distance below the top of the bail and arranged in line endwise; levers 10 operatively attached to the trays at the forward ends of the trays and mounted on the said axles; bars pivotally connected, at one end, to the rear portions of the trays, and pivotally supported, at the other end, below the aforesaid 15 axles, and means for operating the levers.
16. In a clam-shell bucket having two oppositely-arranged suitably-supported trays arranged to swing from or toward each other according as the bucket is opened or closed, 20 the combination of the said trays; a bail arranged centrally and transversely of the bucket; two horizontally-arranged axles supported from the bail below the top of the bail and arranged in line endwise; levers oper- 25 atively attached to the forward portion of one of the trays at opposite sides respectively of the respective tray and fulcrumed to the bail by one of the aforesaid axles; a frame or web connecting the said levers together above the 30 fulcrums of the levers and mounted on the axles; two levers operatively attached to the forward portion of the other of the trays at opposite sides respectively of the respective tray and fulcrumed to the bail by the other 35 of the axles and crossing the first-mentioned levers; a frame or web connecting the second-mentioned levers together above the fulcrums of the levers and mounted on the axles; bars pivotally connected, at one end, to the rear 40 portions of the trays, and pivotally supported, at the other end, below the fulcrums of the levers, and means for operating the levers.
17. In a clam-shell bucket having two oppositely-arranged suitably-supported trays ar- 45 ranged to swing from or toward each other according as the bucket is opened or closed, the combination of the said trays; a bail arranged centrally and transversely of the bucket and provided at the top with coinci- 50 dently-arranged sheaves; upright levers operatively attached to the forward portions of the trays and fulcrumed to the bail; with the axes of the levers parallel with the axes of the trays; sheaves borne by the levers at the 55 upper ends of the levers; bars pivotally connected, at one end, to the rear portions of the trays, and pivotally supported, at the other end, and cables attached, at one end, to the upper portion of the bail, thence leading 60 to and around the sheaves of the lever or levers attached to one of the trays, thence leading leading to and in under the sheaves of the lever or levers attached to the other tray, and thence in under the aforesaid sheaves of the 65 bail.

18. In a clam-shell bucket having two oppositely-arranged suitably-supported trays ar- 70 ranged to swing from or toward each other according as the bucket is opened or closed, the combination of the said trays; a bail ar- 75 ranged centrally and transversely of the bucket and having end members which are arranged a suitable distance apart laterally and an upper central portion comprising two parallel axles extending between the end 75 members of the bail; two levers operatively attached to opposite sides respectively of the forward portions of one of the trays and fulcrumed to the different end members respectively of the bail; two levers operatively at- 80 tached to opposite sides respectively of the forward portion of the other of the said trays and fulcrumed to the different end members respectively of the bail and crossing the first-mentioned levers, with the axes of all of the 85 said levers parallel with the axes of the trays; sheaves borne by the levers at the upper ends of the levers; bars pivotally connected, at one end, to the rear portions of the trays and pivotally supported at the other end; two 90 sheaves on one of the aforesaid axles a suitable distance apart longitudinally of the respective axle; cables attached, at one end, to the other of the aforesaid axles, thence leading to and around the sheaves of the levers 95 attached to one of the trays, thence leading to and in under the sheaves of the levers attached to the other trays, and thence in under the aforesaid axle-sheaves.
19. In a clam-shell bucket having two oppo- 100 sitely-arranged suitably-supported trays ar- ranged to swing from or toward each other according as the bucket is opened or closed, the combination of the said trays; a bail ar- 105 ranged centrally and transversely of the bucket and provided, at the top, with sheaves arranged a suitable distance apart laterally and with their axes parallel with the axes of the trays; upright levers operatively attached to the forward portions of the trays and ful- 110 crumed to the bail; with the axes of the levers parallel with the axes of the trays; sheaves borne by the levers at the upper ends of the levers; bars pivotally connected, at one end, to the rear portions of the trays, and pivot- 115 ally supported at the other end; cables at- tached, at one end, to the upper portion of the bail, thence leading to and around the sheaves of the lever or levers attached to one of the trays, thence leading to and in under the 120 sheaves of the lever or levers attached to the other tray, and thence in under the afore- said sheaves of the bail, and guards borne by the levers and arranged to prevent displace- 125 ment of the cables from the sheaves of the levers.

20. In a clam-shell bucket having two oppo- 130 sitely-arranged trays arranged to swing from or toward each other according as the bucket is opened or closed, the combination of the said

- trays; a bail arranged centrally and transversely of the bucket; levers operatively attached to the forward portions of the trays and fulcrumed to the bail; with the axes of all of the said levers parallel with the axes of the trays and coincident; means for operating the levers; bars pivotally connected, at one end, to the trays rearwardly of the levers, and pivotally supported at the other end; clevises pivoted to the trays, with the axes of the pivotal connection between the clevises and the trays coincident and parallel with the pivotal connections between the aforesaid bars and the trays; guide-sheaves borne by the upper portion of the bail, and cables attached, at one end, to the clevises, thence leading to and in under the said sheaves and thence upwardly.
21. In a clam-shell bucket having two oppositely-arranged trays arranged to swing from or toward each other according as the bucket is opened or closed, the combination of the said trays; a bail arranged centrally and transversely of the bucket; levers operatively attached to the forward portion of the trays and fulcrumed to the bail, with the axes of all of the said levers parallel with the axes of the trays and coincident; means for operating the levers; bars pivotally connected, at one end, to the trays rearwardly of the levers, and pivotally supported at the other end; clevises pivoted to the trays, with the axes of the pivotal connections between the clevises and the trays parallel with the pivotal connections between the aforesaid bars and the trays; guide-sheaves borne by the upper portion of the bail; cables attached, at one end, to the clevises, thence leading to and in under the said sheaves and thence upwardly, and a guard borne by the bail and extending over the sheaves and arranged to prevent displacement of the cables from the sheaves, which guard has holes to accommodate the upward extension of the cables from the sheaves.
22. In a clam-shell bucket having two oppositely-arranged suitably-supported trays arranged to swing from or toward each other according as the bucket is opened or closed, the combination of the said trays; a bail arranged centrally and transversely of the bucket and having end members which are arranged a suitable distance apart laterally and an upper central portion comprising two parallel axles extending between the end members of the bail; levers operatively attached to the forward portions of the trays and fulcrumed to the end members of the bail, with the axes of the levers parallel with the axes of the trays and coincident; means for operating the levers; two clevises pivoted to the different trays respectively, with the pivotal connection between each clevis and the connected tray forming the axis of the said tray; two guide-sheaves on the different aforesaid axles respectively, and cables attached, at one end, to the clevises and thence leading to and in under the different aforesaid sheaves respectively and thence upwardly.
23. In a clam-shell bucket having two oppositely-arranged trays arranged to swing from or toward each other according as the bucket is opened or closed, the combination of the said trays; a bail arranged centrally and transversely of the bucket; levers for actuating the trays from their open into their closed position; means for operating the levers; two clevises pivoted to the different trays respectively, with the pivotal connection between each clevis and the connected tray forming the axis of the said tray; two suitably-spaced guide-sheaves borne by the upper portion of the bail; cables attached, at one end, to the clevises and thence leading to and in under the different sheaves respectively and thence upwardly, and a guard borne by the bail and extending over the sheaves and arranged to prevent displacement of the cables from the sheaves, which guard has holes to accommodate the extension of the cables from the sheaves upwardly through the guard.

Signed by us at Cleveland, Ohio, this 2d day 90 of July, 1904.
